UNITED STATES PATENT OFFICE.

JOSEPH FRANKLIN MORRIS, OF WEST LAFAYETTE, INDIANA.

WASH MACHINE.

Application filed November 15, 1919. Serial No. 338,227.

To all whom it may concern:

Be it known that I, JOSEPH F. MORRIS, a citizen of the United States, residing at West Lafayette, in the county of Tippecanoe and State of Indiana, have invented new and useful Improvements in Wash Machines, of which the following is a specification.

This invention relates to a washing machine and has for its primary object to construct an apparatus of this character capable of more efficiently washing clothes and in such a manner that the minimum amount of energy will be consumed.

An object of the invention is the provision of a basket for holding the clothes of such a construction that the clothes will be subject to a rubbing action and besides to a continuous movement of water so that all the dirt will be forced from the clothes both by the agitation of the water and the rubbing action of the basket.

Besides the above my invention is distinguished in the use of an oscillatory mechanism for the basket capable of being quickly connected to and disconnected from the basket so that the latter may easily move to and be held in a position to allow the clothes to be arranged in the basket or removed therefrom.

With these and other objects in view the invention will be better understood from the following detailed description taken in connection with the accompanying drawings wherein

Figure 1 is a side elevation view of the machine.

Figure 2 is a vertical sectional view thereof.

Fig. 3 is a perspective view of the drive mechanism.

Fig. 4 is a detailed sectional view.

Fig. 5 is a detailed view of a portion of the shaft.

Fig. 6 is a detailed view showing how the link is associated with the shaft.

Again referring to the drawings illustrating one manner in which the invention may be constructed #1 designates a water receptacle supported within the body 2 of the machine. This body 2 includes the top 3

and a door 4, closing and opening 5 in the top. Thus it will be seen that when the door is closed the water is prevented from splashing from the receptacle 1. Mounted for swinging movement in the receptacle 1 is a U shaped shaft 6 journaled in the body 2 and having one end formed into a crank arm 7 for purpose hereinafter described. The basket 8 which is supported by the shaft so as to be oscillated in the receptacle 1 may be of any suitable construction but for the purpose of illustration I have shown basket 8 of wire, which in the arrangement shown has the advantage of rubbing the clothes in the movement of the basket. The basket 8, being formed of wire may be attached to the U shaped shaft 6 in any suitable manner such as by wires, or the like (not shown). This basket is provided with an opening 9 for the insertion of the clothes into the basket and is closed by the lid 10 in the use of the machine.

I have shown in the drawings one construction of mechanism for oscillating the shaft 6 consisting of a drive shaft 11 having a gear connection 12 with the motor 13. This shaft 11 has mounted thereon a disc 14 provided with a pin 15 working within a slot 16 in one arm of a bell crank lever 17. Pivoted to the other arm of the bell crank lever is a link 18 one end of which is formed to provide a slot 19 for the reception of the crank arm 7. By this construction will be seen that the link may be quickly thrown out of engagement with the crank and pressure applied to the crank by the hand of the operator for moving the basket to the position in Figure 2 where the clothes may be readily removed and subject to the wringer 20 supported upon the machine. This wringer may be any of the well known types.

The basket may be held in position shown in Fig. 2 by slipping the ring 21 of the chain 22 over the crank arm.

It is, of course, to be understood that the invention may be constructed in various other manners and the parts associated in other relations and, therefore, I do not desire to be limited in any manner except as

set forth in the claim hereunto appended.
Having thus described the invention, what

I claim is—

In a washing machine, the combination
5 with a receptacle of a substantially U-shaped
shaft within said receptacle, a foraminious
clothes container shaped as a segment of a
cylinder carried by said U-shaped shaft and

movable in said receptacle, said shaft having
a crank portion thereon positioned ex- 10
teriorly of said receptacle, and operating
mechanism connected to said crank portion.

In testimony whereof I affix my signature.

JOSEPH FRANKLIN MORRIS.
